UNITED STATES PATENT OFFICE.

JOHN M. CONNELL AND FRANK E. GRAVES, OF BRAINTREE, MASSACHUSETTS.

SHOE AND METHOD OF MAKING SAME.

Application filed August 15, 1922. Serial No. 581,959.

To all whom it may concern:

Be it known that we, JOHN M. CONNELL and FRANK E. GRAVES, citizens of the United States of America, and residents of 5
5 Braintree, in the county of Norfolk and State of Massachusetts, have invented certain new and useful Improvements in Shoes and Methods of Making Same, of which the following is a specification.

10 This invention relates to shoes and particularly to that class of shoes in which the outsole is sewed directly to the inturned edges of the upper, and has for its object the production of a shoe of this character 15 which may be manufactured without necessitating the turning of the upper.

Another object of the invention is the production by a new method of manufacture of a shoe which will have great flexibility 20 and which may be manufactured at a minimum expense.

The invention consists in turning the edges of the upper inwardly over the insole and permanently securing said inturned 25 edges to said insole, tacking an outsole to said insole at the toe and heel and then uniting said outsole to said inturned edges of the upper by a row of stitches, which pass through the insole only at the heel portion 30 thereof.

The invention further consists in providing the insole with a very narrow shank portion permanently secured only to the inturned edges of the upper and wholly disconnected from the outsole.

The invention further consists in the uniting of the outsole to the inturned edges of the upper by a row of stitches outside of but adjacent to the edge of the forepart of 40 the insole, removed from the edges of the shank of the insole and passing through the heel portion thereof.

The invention further consists in a new method of making a shoe.

45 The invention further consists in certain novel features of construction and arrangement of parts which will be readily understood by reference to the description of the drawings and to the claims to be herein- 50 after given.

For the purpose of illustrating the invention, one preferred form thereof is shown in the drawings, this form having been found to give satisfactory and reliable results, al-

though it is to be understood that the various 55 instrumentalities of which the invention consists can be variously arranged and organized and that the invention is not limited to the precise arrangement and organization of the instrumentalities as herein shown 60 and described, except as required by the scope of the appended claims.

Of the drawings:

Figure 1 represents an inverted plane of a last having an inner sole superimposed 65 thereon.

Figure 2 represents an inverted plan of said last and insole with a layer of fibre board superimposed upon the heel portion 70 of the inner sole.

Figure 3 represents an inverted plan of same with the edges of the upper drawn inwardly over said insole and layer of fibre board and secured thereto by tacks or similar fastening devices.

Figure 4 represents a plan of the outsole 75 to be used, and showing the shank stiffener secured thereto.

Figure 5 represents an inverted plan of the last, innersole, and upper with the outsole superimposed thereon and secured at 80 the toe and heel to said insole and inturned edges of the upper by a plurality of tacks or similar fastening devices.

Figure 6 represents a transverse section 85 on line 6, 6 on Fig. 3.

Figure 7 represents a transverse section on line 7, 7 on Fig. 5.

Figure 8 represents a horizontal section 90 of the shoe through the upper and showing in plan the inner sole and the row of stitches securing the outsole to the inturned edges of the upper and also to the heel portion of the inner sole.

Figure 9 represents a transverse section 95 on line 9, 9 on Fig. 8, the last being shown removed to permit the inturned edges of the upper to be secured to the outsole by a row of stitches formed on an ordinary shoe stitcher.

Figure 10 represents a vertical section on line 9, 9 on Fig. 8 showing the channel flaps positioned over the row of stitches, and

Figure 11 represents a transverse section 105 on line 11, 11 on Figs. 5 and 8, showing the counter, inturned edges of upper, layer of material and inner sole, all united to outsole by row of stitches.

Similar characters indicate like parts throughout the several figures of the drawings.

In the drawings, 10 is a last which may be of any well known construction, this last preferably having secured to the bottom thereof a metal plate 11.

In carrying out the new method of constructing shoes, there is first superimposed upon the metal plate 11 on the bottom of the last 10, an inner sole 12 preferably having a very narrow shank 13, all as indicated in Fig. 1 of the drawings.

The next operation is to position upon the heel portion of the innersole 12 a layer of material 14, preferably of fibre board or some similar stiff material. Then a counter 15 is positioned between the thicknesses of material composing the heel portion of the upper 16.

The upper 16 with the counter 15 therein is then placed upon the last and the edges 17 thereof are drawn over the innersole 12, and layer of material 14, as shown in Fig. 3 of the drawings.

For convenience, in the drawings, except in Fig. 11, the upper 16 when shown in section is shown in one piece, although it is to be understood that said upper consists of the usual outer thickness of leather, the inner thickness of leather and a lining of cloth, all as is the usual practice in the construction of shoes.

The edge 17 of the upper 16 having been drawn into position over the bottom of the last, said edge is secured to the innersole throughout its entire length by a plurality of tacks or similar fastening devices 18, the points of which are forced against the metal plate 11 and are upset thereby, clinching the fasteners and permanently securing together the inturned edge 17 of the upper 16 and the innersole 12.

At the rear portion of the last, these fastening devices 18 pass through the thickness of material 14 and the inturned edge of counter 15.

The outsole 19 to be used in the manufacture of the shoe is provided with a shank stiffener 20 secured to the inner face thereof by fastening prongs 21, or in any other well known manner.

The outer face of the outsole has a channel 22 cut therein forming a lip 23 which, in the construction of the shoe, is turned inwardly as indicated in Figs. 5, 7, and 9 of the drawings.

This outsole 19 is then superimposed on the inturned edge 17 of the upper 16 on the last 10, and the heel portion thereof is then secured to the inner sole 12 and layer of material 14 by a plurality of tacks or other fastening devices 24, while the toe portion thereof is secured to the inturned edge 17 of the upper 15 and the innersole 12 by a plu-

rality of tacks or similar fastening device 25, no tacks or similar fastening devices being used between the heel and toe.

By means of these fastening devices 24 and 25, the outsole 19 is so secured to the in-turned edge 17 of the upper 16 and the inner sole 12 that the parts above referred to will be retained in proper position relatively to each other after the last 10 has been removed from the upper.

In constructing the shoe, the last 10 is now removed from the upper 16. With the last removed, the shoe can be placed upon the horn of a boot and shoe stitcher, and the part 26 of the outsole 19 may be united by a row of stitches 27 to the inturned edge 17 of the upper 16.

This row of stitches 27 uniting the part 26 of the outsole 19 and the inturned edge 17 of the upper 16, is formed adjacent to but outside of the edge of the fore part of the innersole 12 and considerably removed from the shank portion 13 thereof, as indicated in Fig. 8 of the drawings.

Preferably the row of stitches 27 passes at 28 through a part of the heel portion of the inner sole 12, the layer of material 14, the inturned edge of the counter 15, and the inturned edge 17 of the upper 16 thereby firmly securing together these various parts, no stitches being used at the rear of said heel portion.

This operation of stitching having been completed, the shoe is removed from the sewing machine, the lip or flap 23 is turned over into position indicated in Fig. 10 of the drawings, covering the row of stitches 27, said lip or flap 23 being secured to the part 26 by any suitable adhesive.

The shoe is then again placed upon the last 10 and the outsole is subjected to the pressure of a beating-out machine to properly shape the same, the edge is trimmed, and the heel 29 is secured thereto, all in the usual manner.

By this method, a shoe may be constructed similar to the turned shoe, without necessitating the turning of the upper. This greatly reduces the expense of manufacture and also the chances of injuring the shoe during the process of manufacture.

By making the shank portion 13 of the inner sole very narrow, the shank of the shoe may be made much narrower than by the usual method of manufacturing shoes.

This produces a shoe having great flexibility in its shank portion.

In some cases it may be desired to have the finished shoe free from tacks and in this case there is no necessity of using a last with metal plate on its bottom, but an ordinary wooden last can be used.

Under these conditions the tacks 18 are only driven through the inturned edge of the upper and insole and are not upset or

clinched. They are retained therein only long enough to permit a tacky substance inserted between said inturned edges and insole to set sufficiently to secure said edge 5 permanently to said insole. The tacks 18 may be then removed.

In the same manner two or three tacks 25 may be used to hold the outsole in position upon the inturned edge of the upper during the operation of stitching and when the 10 row of stitches 27 has been completed these tacks 25 may be removed.

By this construction a substantially tackless shoe may be manufactured. A shoe 15 constructed by this improved method has great strength, as the row of stitches in the completed shoe is outside of the foot when placed within the shoe and consequently there is no strain upon the stitches 20 as is the case in shoes where the stitches are under the foot.

It is obvious in shoes of the character last mentioned the foot in walking will spread and force the upper outwardly so that there 25 will be a constant pull upon the stitches thus causing them to break.

By having the stitches outside the outline of the foot this objection is wholly overcome in the shoe herein shown and described. Moreover owing to the narrow shank portion of the insole and the upper being drawn in and united to the outsole by stitches considerably outside the edge of the shank portion of the insole, there is at 30 this point absolutely no strain either upon the stitches or the upper and the shoe thus constructed is made very flexible and exceedingly strong.

It is believed that the method of manufacture 40 of shoe, and the many advantages of the shoe when manufactured by this method, will be fully understood from the foregoing description.

Having thus described our invention, we 45 claim:

1. The method of making shoes which consists in placing upon a last an insole having a very narrow shank portion; drawing the edges of the upper over said insole and permanently securing said edges to said insole; positioning an outsole on the inturned edges of the upper and tacking said outsole to 50 said edges and insole at the toe and heel only, said outsole extending at the shank 55 beyond the narrow shank portion of the insole, a distance greatly in excess of that which said outsole extends beyond said edge at the forepart and heel portion; then removing said last; and finally uniting said 60 edges of the upper to said outsole by a row of stitches.

2. The method of making shoes which consists in placing upon a last an insole having a very narrow shank portion; drawing the edges of the upper over said insole and permanently securing said edges to said insole; positioning an outsole on the inturned edges of the upper and tacking said outsole to said edges and insole at the toe and heel only; then removing said last; and finally uniting said edges of the upper to 65 said outsole by a row of stitches, said row of stitches following the edge of the fore part of the insole, being separated a considerable distance from the shank portion thereof and passing through portions of the heel part of the insole and terminating at points opposite the center of said heel part.

3. The method of making shoes which consists in placing an insole upon a last; placing a thickness of material on the heel part; then positioning an upper thereon with a counter between the outer and inner thicknesses of the heel part thereof; drawing the edges of the upper over said insole and permanently securing said edges thereto; tacking to said insole at the toe and heel only an outsole; removing the last; and then securing said edges to said outsole by a row of stitches which follow the edge of the forepart of the insole but lie outside of each edge and the edge of the shank and pass through the front part only of the heel portion of the insole, the counter, and the 80 thickness of material beneath said counter.

4. A shoe having the edges of its upper inturned and permanently secured to the insole by a tacky substance, and an outsole secured to said inturned edges of the upper by a row of stitches, outside of and adjacent to the edge of the fore part of said insole and considerably outside of the shank portion thereof.

5. A shoe having the edges of its upper inturned and permanently secured to an insole, having a narrow shank portion, and an outsole secured to said inturned edges of the upper by a row of stitches outside of and adjacent to the edge of the forepart of the insole, said row of stitches being considerably outside of the edges of said shank portion and extending through the heel portion of the insole thereby uniting said heel portion to said outsole.

Signed by us at Braintree, Mass., this 10th day of August, 1922.
